(57) **CLAIM**

The ornamental design for a combined cosmetic mirror with LED light, as shown and described.

DESCRIPTION

FIG. 1 is a front, top perspective view of a combined cosmetic mirror with LED light, showing my new design; FIG. 2 is a rear, bottom perspective view thereof; FIG. 3 is a rear, top perspective view thereof; FIG. 4 is a front elevation view thereof; FIG. 5 is a rear elevation view thereof; FIG. 6 is a left side elevation view thereof; FIG. 7 is a right side elevation view thereof; FIG. 8 is a top plan view thereof; FIG. 9 is a bottom plan view thereof; FIG. 10 is another perspective view of the combined cosmetic mirror with LED light, shown in an alternative position; FIG. 11 is another perspective view thereof, shown in an alternative position; and, FIG. 12 is another perspective view thereof, shown in an alternative position.

The broken lines in the figures illustrate portions of the combined cosmetic mirror with LED light that form no part of the claimed design.

1 Claim, 12 Drawing Sheets
